DESIGN FOR A LAMP

Joseph M. Angeletti, New York, N. Y.

Application April 20, 1939, Serial No. 84,408

Term of patent 3½ years

To all whom it may concern:

Be it known that I, Joseph M. Angeletti, a subject of the King of Italy and a resident of New York, in the county of New York and State of New York, have invented a new, original, and ornamental Design for a Lamp, of which the following is a specification, reference being had to the accompanying drawing, forming part thereof,

The figure is a view in side elevation of the lamp embodying my new design.

The opposite side of the design is substantially the same in appearance as the side shown in the drawing.

I claim:

The ornamental design for a lamp, as shown and described.

JOSEPH M. ANGELETTI.
